(57) **CLAIM**

The ornamental design for a plate setter lifter, as shown and described.

DESCRIPTION

FIG. 1 is a plan view of a plate setter lifter according to the invention; and

FIG. 2 is a front side view of the plate setter lifter of FIG. 1; and

FIG. 3 is a first side view of the plate setter lifter of FIG. 1; and

FIG. 4 is a second side view of the plate setter lifter of FIG. 1; and

FIG. 5 is a bottom view of the plate setter lifter of FIG. 1; and

FIG. 6 is a back side view of the plate setter lifter of FIG. 1; and

FIG. 7 is a first top perspective view of the plate setter lifter of FIG. 1; and

FIG. 8 is a second top perspective view of the plate setter lifter of FIG. 1; and

FIG. 9 is a first bottom perspective view of the plate setter lifter of FIG. 1; and,

FIG. 10 is a second bottom perspective view of the plate setter lifter of FIG. 1.

1 Claim, 10 Drawing Sheets
